(57) **CLAIM**

The ornamental design for a pocket blade dispenser, as shown and described.

DESCRIPTION

This application is related to U.S. patent application Ser. No. 13/843,609, entitled "Pocket Blade Dispenser" filed here-with.

FIG. 1 is a perspective view of a pocket blade dispenser showing our new design;

FIG. 2 is a left side view thereof;

FIG. 3 is a top view thereof;

FIG. 4 is a bottom view thereof;

FIG. 5 is a right side view thereof;

FIG. 6 is a front view thereof; and,

FIG. 7 is a rear view thereof.

The broken lines depict portions of the pocket blade dispenser in which the design is embodied that are not considered part of the claimed design.
